UNITED STATES PATENT OFFICE

THOMAS A. ADAMS, OF BRENHAM, TEXAS

FILLING-FEELER-KNIFE TRIPPER

Application filed September 14, 1928. Serial No. 305,961.

The present invention relates to improvements in attachments for filling replenishing looms and has reference more particularly to a filling thread cutter tripping mechanism.

5 One of the important objects of the present invention is to provide a filling feeler knife tripper that includes a horizontally disposed arm for attachment at its inner end on the end of the breast beam associated with the 10 hopper stand, said arm extending forwardly for disposition adjacent the shuttle feeler and carrying at its outer end a pivoted trip member that cooperates with the laterally projecting pin carried by the heel of the feeler 15 thread cutting mechanism whereby said cutting mechanism will be opened upon the return or forward movement of the shuttle feeler.

A further object is to provide a filling feeler 20 knife tripper of the above mentioned character which will at all times be positive and efficient as well as automatic in its operation, the device being readily and easily attached to the loom without necessitating any material alterations.

A further object is to provide a device of the above mentioned character that will tend to eliminate many broken bobbins and shuttles which results from the use of the type of 30 knife trippers now in use.

Furthermore a knife tripper of this character will permit the shuttle to be set closer to the lay thus permitting the filling knife to operate more efficiently.

35 A still further object resides in the provision of a filling feeler knife tripper which is simple in construction, inexpensive, strong and durable and further well adapted to the purposes for which it is designed.

40 Other objects and advantages will become apparent during the course of the following description.

In the accompanying drawings, forming a part of this specification, and in which like numerals indicate like parts throughout the same:

Figure 1 is a perspective view showing portions of a filling replenishing loom with my improved tripping device associated therewith,

Figure 2 is a side elevation of the supporting arm and the attaching bracket showing the pivoted trip in section,

Figure 3 is a perspective view of the horizontally disposed arm and the attaching bracket therefor,

Figure 4 is a top plan view of the device per se,

Figure 5 is a detail perspective view of the trip element per se, and

Figure 6 is a front elevation of a trip element showing the same mounted on the horizontally disposed arm, the latter being shown in section.

In the drawings wherein for the purpose of illustration is shown the preferred embodiment of my invention, the numeral 1 designates a portion of the breast beam of a loom on which is adapted to be mounted the hopper stand not shown in the usual manner.

The shuttle feeler of the loom is shown at 2 and the same is pivotally supported at its lower end on the stub shaft 3 in the manner also well known in the art. The upper laterally disposed portion 4 of the shuttle feeler has associated with the outer end thereof the conventional cutting mechanism denoted generally by the reference character 5 and as the cutting mechanism is of the conventional construction, a disclosure thereof in the present instance is believed unnecessary.

The heel 6 that forms a part of the cutting mechanism carries the usual laterally projecting pin 7 which pin provides means for cooperation with a tripping mechanism to open the cutter and the tripping mechanism that constitutes the present invention will be hereinafter described in detail.

The shuttle feeler 2 is adapted for swinging movement transversely of the loom and the usual guide bracket 8 is provided for cooperation with the shuttle feeler in the manner also well known in the art.

My improved filling feeler knife tripper is shown generally at 9 in the drawings and the same comprises an angular attaching bracket that includes a rectangular shaped plate 10 for disposition across the top of the beam 1, said plate being formed with a central opening to accommodate the securing

bolt 11, which bolt is also employed to fasten the hopper stand on the beam.

The opening through which the bolt 11 passes is indicated at 12. The forward end 5 of the plate 10 is bent downwardly to form a flange 13 that engages with the front edge portion of the beam 1 in the manner as suggested very clearly in Figures 1 and 2.

Extending outwardly from the depending 10 flange 13 in a horizontal plane is the arm 14, the same being preferably disposed adjacent the outer end of the pin 7. The outer end of the arm 14 is formed with the spaced openings 15.

15 The tripper 9 further includes the provision of a trip element 16 shown in detail in Figure 5 and this trip element comprises a body 17 that is formed with a longitudinal through slot 18 and extends from the forward to the rear of said body. The upper inner corner portion of the body is cut away whereby to provide a relatively small yoke 19 at the upper forward corner of the body. Furthermore, the slot 18 is of increasing 20 length from the rear to the forward edge of the body as is more clearly indicated in Figure 2 of the drawings, the lower edge of the slot at the rear edge portion of the body constituting a stop or shoulder 20 for a purpose also to be presently described.

The lower forward corner portion of the body is rounded to form the cam face 21. The body 17 is formed with registering openings in the opposed sides of the slotted portion thereof and the arm 14 is disposed through the longitudinal slot 18 and a cotter pin or the like shown at 22 extends through the registering openings formed in the sides of the slotted portion of the body and 35 through either one of the openings 15 formed in the outer end portion of the arm 14 whereby to pivotally suspend the trip element 16 on the outer end of the horizontally disposed arm 14.

40 The yoke 19 will engage the upper edge of the bar 14 to limit the rearward swinging movement of said trip element while the inclined bottom face 23 of the slot 22 will limit the forward swinging movement of the trip element.

45 The trip element is suspended from the bar 14 so as to be disposed in the path of movement of the laterally projecting pin 7. The operation of my improved tripping device 50 may be briefly stated as follows. As the shuttle feeler 2 moves rearwardly to an operative shuttle feeling position, the pin 7 comes in contact with the cam surface 21 of the trip element 17 and is thus forced down to open 55 the thread cutter 5, the pin passing beneath the lower corner of the trip.

60 As the shuttle feeler 2 returns to its normal position, the pin 7 will strike the straight rear edge portion of the trip 16 and will cause 65 said trip to swing upwardly and forwardly

on the pivot 22 so as to permit the pin 7 to pass underneath of the trip and after the pin 7 has passed underneath of the trip during the forward swinging movement of the shuttle feeler, said trip will by gravity return to its normal position as shown in Figure 2.

The shoulder 20 will then abut with the lower edge of the arm 14. The yoke 19 will limit the rearward swinging movement of 75 the trip when the pin travels along the cam surface 21 of the trip as is obvious from the construction illustrated.

It will thus be seen from the foregoing description, that I have provided a yielding 80 trip for association with the cutter mechanism for positively and efficiently opening the cutter at the proper time, and this operation being entirely automatic.

A tripping device of the above mentioned 85 character can be readily and easily installed on a loom without necessitating any material alterations of the parts of the loom with which the tripping device is to be associated.

Furthermore my improved tripping device 90 will be strong and durable and inexpensive in its manufacture. While I have shown the preferred embodiment of my invention, it is to be understood that various changes in the size, shape and arrangement of parts may be 95 resorted to without departing from the spirit of the invention and the scope of the appended claims.

Having thus described my invention, what I claim as new is:

1. In a filling replenishing loom, the combination of a stationary beam, a shuttle feeler, and the thread cutting mechanism carried by said shuttle feeler including the usual heel portion and a laterally projecting pin 105 carried thereby; of a horizontally disposed arm secured at its inner end to said beam, and a trip element pivotally suspended from the outer end of said arm for disposition within the path of movement of the pin, said trip element cooperating with the pin to effect the opening of the cutting mechanism during the swinging movement of the shuttle feeler in one direction, said trip element comprising a body formed with a longitudinal slot through which the horizontal arm extends, a pivot pin extending through the slotted portion of the body and said arm, said body being formed at its lower outer corner with a cam face with which said laterally projecting pin engages. 110

2. In a filling replenishing loom, the combination of a stationary beam, a shuttle feeler, and the thread cutting mechanism carried by said shuttle feeler including the usual heel portion and a laterally projecting pin 115 carried thereby; of a horizontally disposed arm secured at its inner end to said beam, and a trip element pivotally suspended from the outer end of said arm for disposition 120

within the path of movement of the pin, said trip element cooperating with the pin to effect the opening of the cutting mechanism during the swinging movement of the shuttle
5 feeler in one direction, said trip element comprising a body formed with a longitudinal slot through which the horizontal arm extends, a pivot pin extending through the slotted portion of the body and said arm, said body being formed at its lower outer corner with a cam face with which said laterally projecting pin engages, said slotted body being formed with a stop portion for cooperation with the bar to limit the swing movement of the pivoted trip element in one direction.

3. A tripping device of the class described, a bracket for attachment to the beam of a loom, an arm extending horizontally and outwardly from the bracket for disposition adjacent the shuttle feeler of a loom, and a pivoted trip suspended from the outer end of the arm for cooperation with the laterally projecting pin of the heel portion and a conventional cutter carried by the shuttle feeler for opening the cutter when the shuttle feeler moves in one direction, said trip element comprising a body formed with a longitudinal slot extending from the front to the rear side thereof through which the horizontal arm extends, the upper inner corner portion of the body being cut away to provide a yoke at the upper forward corner of the body, said slot being of increasing length from the rear to the forward edge of the body, a pivot pin extending through the slotted portion of the body and said horizontal arm, the lower edge of the slot at the rear portion of the body forming a stop to limit the forward swinging movement of said trip element, the lower forward corner portion of the body being rounded to form a cam face with which said laterally projecting pin engages, said yoke cooperating with the lower edge of said horizontal arm to limit the swinging movement of the trip element in one direction as and for the purpose described.

In testimony whereof I affix my signature.
THOMAS A. ADAMS.
